BOTTOM HOLE CHOKE FOR PLUNGER
LIFT DEVICESHarold W. Fletcher, Houston, Tex., assignor to
Hughes Tool Company, Houston, Tex., a cor-
poration of Texas

Application January 9, 1932. Serial No. 585,695

4 Claims. (Cl. 103—52)

My invention relates to a flow choke to be employed at the lower end of the eduction tube in a plunger lift apparatus.

It is an object of the invention to check the flow of fluid from the well into the eduction tube so as to allow smoother and more effective operation of the apparatus.

In raising the plunger with its load of liquid to the surface without a choking means at the lower end of the tube the gas and liquid from the well tend to rise quickly behind the plunger and to blow up behind the same and prevent the proper dropping of the plunger after its working stroke. I contemplate avoiding this difficulty by slowing down the entrance of fluid to the tube.

In the drawing herewith, Fig. 1 is a central longitudinal section through a plunger lift equipment at the upper end of the installation.

20 Fig. 2 is a similar sectional view of the lower end of the installation shown in position in the well.

I have shown the well as equipped for at least a portion of the distance into the well with a 25 casing 1 projecting above the ground and having at its upper end a casing head 2. Said casing head has a lateral branch 3 through which fluid may enter or pass from the well. This line may be controlled by a hand-operated valve 4. The 30 upper end of the casing head is threaded at 5 for engagement with a bonnet 6, which is reduced in diameter at its upper end and threaded internally at 7 for engagement with the eduction tube extension 8.

35 Within the casing head is an inwardly projecting flange 9 upon which is supported the head 10 secured to the upper end of the eduction tube 11. Said head has a radial flange resting upon the shoulder 9 and making a close fit with the interior of the casing head. A gasket 12 may be placed upon the shoulder 9 to assure a fluid seal between the tube and the lower portion of the casing head.

The eduction tube 11 projects from the surface 45 downwardly so as to submerge the lower end within the liquid in the well. The lower end may be provided with a strainer plug 13 thereon. Said plug is connected by means of a coupling 14 to the lower end of the tube, and fitting within 50 the coupling and secured between the ends of the plug and the tube is a ring or collar 15 upon which is supported the bottom choke member 16. Said choke member is adapted to fit closely within the tube at its lower end and is tapered 55 upwardly so as to be engaged by a locking collar

17 and thus held frictionally within the tube. The choke member is provided at its lower end with an inlet orifice 18, which is of the proper size to restrict the flow of fluid from the well to the interior of the eduction tube. 60

Above the orifice 18 the passage 19 is flared upwardly to discharge within the passage 20 through the clamping collar.

The clamping collar is cylindrical on its outer surface and has its interior beveled or flared 65 downwardly to engage over the upper end of the choke member and wedge the said member rigidly in position. The opening through the upper end of the clamping collar through which the fluid passes also furnishes engagement for a 70 spear or grab by means of which the clamping member may be removed from the tube.

The head 10 at the upper end of the eduction tube is formed on its inner surface to fit closely against the lower end of the eduction tube extension 8. This connection makes a close joint between the head and the tube extension, allowing the rotation on said extension when the tube or the bonnet 6 with the tube therein is secured in position. Within the casing head the tube extension is provided with longitudinal openings 21 through which the fluid from the tube may be discharged. The upper end of the extension is closed by a cap 22, which may have therein a sleeve 23 of rubber or other compressible material, furnishing a buffer or shock absorbing member when the plunger rises beyond its usual height. At one side of the casing head 2 and connected with the chamber 24 within the casing head is the discharge outlet 25 through which 90 the fluid may pass to storage.

The plunger shown herein is of the usual form now generally employed in this apparatus and comprises a body 26 cylindrical on its outer surface and having its inner wall converging downwardly to provide a stream line passage for fluid through the same. At the lower end of the body is connected the ring 27 having a valve seat 28 thereon and connected with a supporting block 29 by means of legs 30. The block 29 has a circular recess 31 at its upper end to support the valve 32 in position spaced below the seat when the valve is in open position. The valve stem 33 projects through a guide opening in the block 29 and the fluid within the tube has access to the 100 lower end of said valve stem through openings 34 in the lower end of the block 29.

In the operation of this device the gas produced from the well will accumulate in the space 35 between the wall of the well and the eduction 110

tube and will force the liquid upwardly in the eduction tube above the seat provided at the upper end of the clamping sleeve 17. When sufficient head of liquid is accumulated above the 5 plunger back pressure will be exerted upon the gas entering the lower end of the tube sufficient to cause the gas below to raise the valve 32 to its seat after which the plunger with its load of liquid will be raised to the surface, discharging 10 the liquid through the openings 21 to the discharge pipe 25.

When the plunger has passed the openings 21 it will move into the closed upper end of the tube 15 extension and the valve will be forced open by the back pressure of fluid trapped in the upper end of the tube. The plunger will thus be allowed to drop back in the tube to the lower end thereof ready to repeat the operation.

It has been found, however, that where the 20 flow of gas and liquid at the lower end of the tube is allowed to operate unchecked that it will interfere with the dropping of the plunger and in some cases may even force the valve to closed position. It is to overcome this situation that the 25 choke member 16 is provided. The gas and liquid can enter only at a gradual and slow rate of speed sufficient to raise the liquid above the seat in the clamping collar 17 but not in such amount as to interfere with the smooth operation 30 of the plunger on its downward stroke. It will be obvious that the size of the orifice 18 in the choke member may be varied to suit the circumstances in the particular well being operated, and if conditions change it is possible to lower a 35 spear into the well and remove the choke member and substitute therefor another one of the choke devices properly regulated as desired.

What I claim as new is:

1. In a plunger lift device, a single string of eduction tube therein, means adjacent the upper end thereof to allow discharge of fluid therefrom, a choke member in said tube adjacent the lower end to retard the passage of both gas and liquid into said tube, a clamping collar securing said choke member rigidly in position, and a plunger movable by fluid pressure above said choke member.

2. In a plunger lift device, an upper well casting, a single string of eduction tube therein, means adjacent the upper end thereof to allow discharge of fluid therefrom, a choke member in said tube adjacent the lower end to retard the passage of fluid into said tube, said choke member comprising a plug for said tube having a restricted orifice therein, and a clamping collar wedging about said plug to hold the said plug in position.

3. In a plunger lift device including a single string of eduction tube and a plunger working freely therein from the lower end to the upper end thereof, the combination of a choke device limiting the rate of flow of fluid to said tube and a seat for said plunger above said choke.

4. In a plunger lift device for wells including an eduction tube and a plunger movable therein from the lower end to the upper end thereof, the improvement comprising raising said plunger in said tube by the force of gas accumulating in the 105 well and checking the flow of fluid into the lower end of said eduction tube, to prevent a strong flow of gas upwardly in said tube after said plunger has reached its upper limit of movement and thus allowing said plunger to drop 110 back.

HAROLD W. FLETCHER.
